LUMINAIRE

Donald P. Cianca, Elmhurst, Ill., assignor to Joslyn Mfg. and Supply Co., Chicago, Ill., a corporation of Illinois

Filed Mar. 5, 1965, Ser. No. 84,117

Term of patent 14 years

(Cl. D48—31)

FIG. 1

FIG. 2

FIG. 3

The dominant features of my design reside in the portions shown in full lines.

I claim:

The ornamental design for a luminaire, substantially as shown and described.
